DESIGN FOR A DISPLAY TRAY FOR COSMETIC CONTAINERS OR THE LIKE

Mary Dresselhouse, Flushing, N. Y.

Application August 20, 1937, Serial No. 71,213

Term of patent 3½ years

To all whom it may concern:

Be it known that I, Mary Dresselhouse, a citizen of the United States of America, residing at Flushing, in the county of Queens and State of New York, have invented a new, original, and ornamental Design for a Display Tray for Cosmetic Containers or the like of which the following is a specification, reference being had to the accompanying drawing, forming a part thereof:

for cosmetic containers or the like showing my new design.

I claim:

The ornamental design for a display tray for cosmetic containers or the like as shown.

MARY DRESSELHOUSE.
